SAFETY MOUNT FOR AN OUTBOARD MOTOR

Alva D. Downs, Quanah, Tex.

Application October 20, 1953, Serial No. 387,201

3 Claims. (Cl. 115—41)

This invention relates to a safety mount for an outboard motor and has for its primary object to prevent injury to the rudder and propeller of a conventional outboard motor through contact with submerged obstacles.

Another object is to elevate the outboard motor to lift the propeller and rudder thereof above the bottom of a boat when a submerged obstacle is encountered.

A further object is to connect to an antenna carried by the boat adjacent the bow thereof operating means by which the outboard motor may be elevated when the antenna encounters a submerged obstacle and at the same time retard the speed of rotation of the propeller of the outboard motor.

The above and other objects may be attained by employing this invention which embodies among its features an outboard motor support carried by the stern transom of a conventional outboard motor boat for up and down movement relative to said transom, yielding means carried by the transom and connected to the support for elevating the motor support to lift above the level of the bottom of the boat the propeller of an outboard motor carried by the motor support, a latch carried by the transom and operatively engaging the motor support for releasably holding said support down and the propeller of the outboard motor below the level of the bottom of the boat, antenna means carried by the boat and projecting downwardly below the bottom thereof in advance of the transom, and means operatively connected to the antenna means and to the latch for exerting releasing effort on the latch when the antenna means encounters a submerged obstacle.

Other features include means connected to the antenna means and to the outboard motor carried by the motor support for retarding the speed of rotation of the propeller of the outboard motor when the antenna means engages a submerged obstacle.

In the drawings:

Figure 1 is a side view in elevation of a boat showing this improved safety motor mount attached thereto;

Figure 2 is a top plan view of Figure 1;

Figure 3 is a fragmentary enlarged sectional view taken substantially on the line 3—3 of Figure 2;

Figure 4 is a fragmentary enlarged sectional view taken substantially on the line 4—4 of Figure 3;

Figure 5 is a fragmentary enlarged sectional view taken substantially on the line 5—5 of Figure 4; and

Figure 6 is an enlarged fragmentary perspective view of the transom of the boat showing the motor mount and motor in place, in which view the motor is illustrated as being elevated.

Referring to the drawings in detail, a conventional outboard motor boat designated generally 10 comprises a hull 12 having a bow 14 and a conventional stern transom 16. The boat is conventionally provided with cross seats 18 for the accommodation of passengers, and carried by the hull 12 and extending inwardly therefrom above the seats 18 are brackets 20 in which a suitable duct 22 is removably supported.

Removably clamped as by C-clamps 24 to the transom 16 is a bed plate 26 carrying adjacent its upper edge an outwardly extending flange 28 which, as illustrated in Figure 3, engages the upper edge of the transom 16 when the bed plate is in place. Carried by and extending outwardly from the face of the bed plate remote from that which engages the transom 16 are spaced parallel guideways 30 which extend perpendicularly with relation to the flange 28 and have secured adjacent their upper ends

5 a transversely extending substantially U-shaped handle 32 by means of which the device may be conveniently handled. Lugs 34 project outwardly from the bed plate 26 adjacent the upper end thereof and are provided with openings for the reception of eyes 36 having screw-threaded shanks which project through the openings in the lugs 34 and are equipped with thumb nuts 38.

10 Mounted for up and down sliding movement in the guideways 30 is an outboard motor support designated generally 40 which comprises an inverted U-shaped body carrying an elongated plate 42 which slides in the guideways 30 and a spaced parallel pad 44 which extends upwardly and over the upper edge of the transom 16 to lie adjacent the rear side thereof and provide a supporting pad for the outboard motor designated generally M.

15 Carried by the plate 42 and projecting outwardly therefrom adjacent the lower end thereof is a treadle 46 and carried by said bed plate adjacent the treadle and on opposite sides thereof are arms 48 to which the lower ends of retractile coil springs 50 are coupled. The upper ends of the retractile coil springs 50 are engaged in the eyes 36 so as to exert elevating effort on the outboard motor support 40 to cause the motor M to be elevated so that the propeller P, and rudder R thereof will be 20 yieldingly held above the level of the bottom of the boat. Carried by the outboard motor support 40 and extending outwardly from the plate 42 thereof adjacent one of the guideways 30 is a toothed bar 52 which, as will be more fully hereinafter explained, holds the outboard motor support 40 in its lowered position with the rudder R and propeller P of the motor M submerged below the bottom 25 of the boat. Carried by the bed plate 26 adjacent one of the guideways 30 is a latch housing 54 having a yieldingly projected latch 56 which moves longitudinally in a rectilinear path which intersects the path of movement of the toothed bar 52 so that when the outboard motor support 40 is pressed downwardly by the treadle 46 to its fullest extent, it will be locked against upward movement under the influence of the springs 50 by the latch 56.

30 Carried by the bed plate 26 and extending outwardly therefrom adjacent the side thereof carrying the latch 56 is an arm 58 to which is pivotally connected for movement in a substantially horizontal arcuate path a lever 60 which is connected intermediate its ends by means of a flexible coupling 62 with an extension 64 carried by the latch 56 so that as the lever is moved away from the longitudinal axis of the boat about its pivot, pull will be exerted on the connection or coupling 62 to move the latch 56 against its yielding means and retract it from engagement with the toothed bar 52. A retractile coil spring 64 is connected adjacent one end to the lever 50 intermediate the ends thereof and at its opposite end to the bed plate 26 to yieldingly urge the lever 60 toward the longitudinal axis of the boat. It will be obvious that from the structure thus far described the outboard motor M may be lowered by stepping on the treadle 46 and moving the outboard motor support downwardly against the effort of the springs 50 and that while so moving the outboard motor support, the latch 56 will be engaged by successive teeth of the toothed bar 52 so as to hold the rudder R and propeller P a selected depth below the bottom of the boat. Also, it will be obvious that upon movement of the lever 60, to exert pull on the flexible member 62, the latch 56 may be withdrawn from engagement with the toothed bar 52 to permit the outboard motor M to be elevated under the influence of the springs 50.

35 In order to render the elevation of the motor M automatic, I mount on the bow of the boat a yoke designated generally 66 which comprises divergent arms which are adapted to be attached to the gunwales of the boat adjacent the bow thereof, and carried by the arms 68 and extending downwardly along the prow of the boat is a shoe 70. Suitable braces 72 extend downwardly and forwardly from the arms 68 to the shoe 70, as will be readily understood upon reference to Figure 1. Carried by the shoe 70 and extending downwardly and forwardly therefrom is an arm 74 to which is pivotally connected for movement in a substantially vertical arcuate path below the forward end of the boat a trip lever 76 which serves as an antenna which is engaged by a submerged

3

obstacle lying in the path of advance of the boat. It will thus be seen that when the trip lever 76 or antenna encounters a submerged obstacle, it will be moved about its pivotal connection with the arm 74 in a vertical arcuate path. Pivots connected intermediate its ends to the arm 74 intermediate the ends thereof is a trigger lever 78 which is connected through the medium of a link 80 to the trip lever 76 remote from its pivotal connection to the arm 74. It will thus be seen that as the trip lever 76 moves in its arcuate path, the trigger lever 78 will move in unison therewith.

move in unison therewith. A retractile coil spring 82 is connected to the trigger lever 78 adjacent the upper end thereof and to the boat 10 so as to yieldingly urge the upper end of the trigger lever 78 toward the stern of the boat and the trip lever 76 forwardly in its arcuate path. Connected to the trigger lever 78 adjacent the upper end thereof is a flexible member 84 which is extended over a suitable guide pulley 86 carried by the boat and thence through the duct 22, to be connected through a suitable coupling unit 86 to a selected position on the lever 60. It will thus be seen that when an obstacle is encountered by the trip lever 76, the trigger lever 78 will be moved in a direction to exert pull on the flexible member 84 to thereby move the lever 60 against the effort of the spring 64 and extract the latch 56 from engagement with the toothed bar 52. Such disengagement of the latch 56 from the bar 52 will permit the outboard motor support 40 to move upwardly in the guideways 30 under the influence of the springs 50 to lift the outboard motor M with the propeller P and rudder R lying above the level of the bottom of the boat.

In order to avoid the racing of the motor M upon the extraction of the propeller P from the water, a cable 88 is connected to the trigger lever 78 and is extended around a suitable guide pulley adjacent the guide pulley 86 and through the duct 22 over a suitable guide pulley 90 mounted on the boat 10 adjacent the transom 16 and coupled to the cable 88 adjacent the transom 16 is a retractile coil spring 92 which is connected to the throttle lever T of the outboard motor M. It will thus be seen that when the trigger lever 78 is operated by the trip lever 76, pull will be exerted on the cable 88 to move the throttle T of the outboard motor M to a slow or stop position.

In some instances it may be found desirable to select the depth to which the propeller P and rudder R of the motor M are submerged in the water in which event a suitable jack designated generally J may be supported on the treadle 46 with its elevating mechanism engaging the handle 32 so that upon movement of the jack handle H in a selected direction, the jack may be actuated to separate the treadle 46 from the handle 32 in a step by step motion so that the latch 56 may be engaged with a selected tooth in the toothed bar 52 to retain the outboard motor M in the selected position.

While in the foregoing there has been shown and described the preferred embodiment of this invention, it is to be understood that minor changes in the details of construction, combination and arrangement of parts may be resorted to without departing from the spirit and scope of the invention as claimed.

What is claimed is:

1. A safety mount for an outboard motor comprising a bed plate adapted to be supported on the stern transom of a boat, a flange carried by the bed plate and extending outwardly therefrom adjacent the upper edge thereof for engaging the top edge of the transom, clamps carried by the bed plate and engaging the transom for clamping the bed plate thereto, spaced parallel guideways carried by the bed plate on the side thereof remote from the flange, said guideways extending perpendicularly with relation to the flange, lugs carried by the bed plate and extending outwardly from its upper edge on the side thereof adjacent the guideways, a substantially U-shaped handle carried by the guideways and extending outwardly therefrom adjacent the upper ends thereof, an inverted

U-shaped outboard motor support mounted in the guide-ways to move up and down therein, one leg of said motor support defining a pad adjacent the rear of the transom against which an outboard motor is clamped, a treadle carried by the opposite leg of the motor support and extending outwardly therefrom adjacent the lower end thereof, arms carried by the motor support and extending outwardly therefrom adjacent the treadle, retractile coiled springs connected to the lugs and to the arms for exerting lifting effort on the motor support, a toothed bar carried by the leg of the motor support carrying the treadle, said bar being movable in unison with the motor support, a latch carried by the bed plate for movement into and out of engagement with the toothed bar, a lever mounted in advance of the motor support and extending downwardly below the level thereof, and said lever being operatively connected to the latch for disengaging it from the toothed bar when a submerged obstacle is engaged by the lever.

20 2. A safety mount for an outboard motor comprising
a bed plate adapted to be supported on the stern transom
of a boat, a flange carried by the bed plate and extending
outwardly therefrom adjacent the upper edge thereof
for engaging the top edge of the transom, clamps car-
ried by the bed plate and engaging the transom for
clamping the bed plate thereto, spaced parallel guide-
ways carried by the bed plate on the side thereof remote
from the flange, said guideways extending perpendicular-
ly with relation to the flange, lugs carried by the bed plate
and extending outwardly from its upper edge on the side
thereof adjacent the guideways, the substantially U-
shaped handle carried by the guideways and extending
outwardly therefrom adjacent the upper end thereof, an
inverted U-shaped outboard motor support mounted on
the guideways to move up and down therein, and one leg
of said motor support defining a pad adjacent the rear of
the transom against which an outboard motor is clamped

3. A safety mount for an outboard motor comprising a bed plate adapted to be supported on the stern transom of a boat, a flange carried by the bed plate and extending outwardly therefrom adjacent the upper edge thereof for supporting the edge of the transom, clamps carried by

engaging the top edge of the transom, clamps carried by the bed plate and engaging the transom for clamping the bed plate thereto, spaced parallel guideways carried by the bed plate on the side thereof remote from the flange, said guideways extending perpendicularly with relation to the flange, lugs carried by the bed plate and extending outwardly from its upper edge on the side thereof adjacent the guideways, the substantially U-shaped handle carried by the guideways and extending outwardly therefrom adjacent the upper end thereof, an inverted U-shaped outboard motor support mounted on the guideways to move up and down therein, one leg of said motor support defining a pad adjacent the rear of the transom against which an outboard motor is clamped, arms carried by the motor support and extending outwardly therefrom, adjacent the lower edge thereof, retractile coiled springs connected to the lugs and to the arms for exerting lifting effort on the motor support, a toothed bar carried by the leg of the motor support opposite the pad, said bar being movable in unison with the motor support, a latch carried by the bed plate for movement into and out of engagement with the toothed bar, and means carried by the boat in advance of the motor support and extending downwardly below the bottom thereof, and said means being operatively connected to the latch for disengaging it from the toothed bar when a submerged obstacle is engaged by the lever.
